UNITED STATES PATENT OFFICE.

ALLAN CYRUS RUSH, OF LOS ANGELES, CALIFORNIA, ASSIGNOR OF ONE-HALF TO
HENRY L. MILLER, OF GLENDALE, CALIFORNIA.

OCEAN PIER.

1,423,884.

Specification of Letters Patent. Patented July 25, 1922.

Application filed February 10, 1920. Serial No. 357,681.

To all whom it may concern:

Be it known that I, ALLAN CYRUS RUSH, a citizen of the United States, residing at 1636 McCullom Street, Los Angeles, in the 5 county of Los Angeles and State of California, have invented a new and useful Improvement in Ocean Piers, of which the following is a specification.

This invention is more particularly intended for piers subjected to ocean wave action, but it is understood that it may be employed wherever desired.

An object of the invention is to provide practical means for extending land for the 15 landings of vessels, pleasure resorts or warehouses into the ocean or other bodies of water and to insure against the destruction of the same by wave action, and also to provide against flooding or spraying the 20 surface of the land, promenade, roadway or the like by high seas or other wave action.

The invention comprises a wave resisting structure of an elongate horse shoe form. The arch of the horse shoe being seaward 25 and the terminals of the horse shoe landward and extending indefinitely parallel to each other as occasion may demand, and spaced from the land or connected thereby directly or by any suitable means, such as draw, 30 bascule or stationary bridges.

A feature of the invention consists in a new and useful form imposed upon the upper portion of the structure and consists in a wave deflecting bead or ledge arranged 35 above normal high water level and surrounded by a guard extending above the deflecting bead a sufficient distance to intercept the splash and sloppings from the waves.

40 Another feature of the invention is the use of a shorter pile driven in between any four adjacent piles, to increase the solidity of the sub-foundation, and also serves as an additional anchor for the concrete matrix above.

Other objects, advantages and features of invention may appear from the accompanying drawings, the subjoined detailed description and the appended claims.

50 The accompanying drawings illustrate the invention.

Figure 1 is a perspective view of a pier constructed in accordance with this invention.

tion partly in place and partly exposed for clearness of illustration.

Fig. 2 is a fragmental broken plan to illustrate the invention.

Fig. 3 is a transverse section of one of the terminal legs.

Fig. 4 is a diagrammatic plan illustrating 60 the distribution and arrangement of the piles.

Fig. 5 is a fragmental diagonal sectional view of the foundation, illustrating the use of the shorter pile and the union of the concrete with the piles and ocean bed.

The pier is constructed upon a suitable sub foundation, and where the pier is built above a sandy or loose bottom, piles 1 may be driven into such bottom, and by means of 70 coffer-dams, not shown, the heavy structure of the pier will be constructed on the sub foundation thus formed with such bottom and piles.

In such case the piling will first be driven 75 into the soft bottom and will then be cut off to leave the tops thereof a desirable distance, say five or more feet below the normal level of the ocean floor. Then a concrete or other suitable superfoundation will be imposed 80 upon the sub foundation formed by said piles and the earth into which they have been driven.

In practice the concrete may extend below the tops of the piles so that the concrete 85 forms a matrix which is embedded in the earth and in which matrix the tops of the piles are embedded and held in place.

The superfoundation 2 of concrete thus laid may be of any suitable thickness, say 90 two to six feet, more or less, and will preferably be in the form of the frustum of a triangle, the apex *a* of which would terminate approximately at the level of the surface 3 of the pier when completed.

When the concrete foundation or bed has 95 thus been completed, its top surface should be somewhat below the normal level of the ocean floor *b*. The bottom of the concrete super base thus formed may in the instance 100 illustrated, be considered to be about five feet below the normal level of the ocean floor. Upon this concrete bed, courses *d* of granite or other substantial stone is well constructed, and in the form shown, the same is built of 105 blocks 4 of granite hewn to form and secured

together by dowel pins 5 and concrete mortar 6; and said stone is laid with broken joints and the individual stones are of as large dimensions as available and convenient.

The granite or other heavy stone structure will extend as a facing 7, toward the wave receiving side at the arch 8, and along both legs 9 and will extend a requisite distance 10 toward the inner face of the pier.

In practice it is deemed advisable to extend said cut stone work well in beyond the central plane of the stone structure and against the inner faces of such structure 15 there may be formed a backing 10 of broken stone or any suitable material.

The exterior face at about eight feet above normal high water level c is formed as a ridge or bead 11 and the surface 12 of 20 the structure below the ridge is an ogee, tangent to the upward inward slope of the base. Above said ridge the surface is formed with a substantially upright face 13 extending from the horizontal surface 3 of the structure, downward to the formation of a smaller 25 ogee tangent to the inward slope of the upper face of said ridge or bead.

The piles 1 are spaced apart a distance of eight feet more or less in each direction; and 30 where it is deemed advisable, an extra, shorter pile may be driven in the center between any four adjacent piles, to render its own service and to brace the other piles by crowding the sand tighter against them.

35 During the building or after the structure has been completed, the space confined by the arch and legs of the structure and such coffer-dams as may be required at the terminals, will be filled with land forming material such as sand or other loose material which may be pumped from the ocean bed to 40 deepen the channels outside the pier or from the main land. Such material may be pumped from any practical distance either 45 from the ocean bed or the shore until, when the pier is completed, an internal filling 14 will have been made entirely within the stone structure. Said stone structure may have a width at the surface of about 25 feet more 50 or less for a pier of 600 feet in width.

It is deemed advisable to construct the pier of such length as to provide a site for pleasure grounds or for commercial manufacturing or other purposes and for the 55 landing of vessels.

The piles are preferably arranged quincuncially as shown in Fig. 4 and one of each five piles may be shorter than the other four

piles and may be driven centrally of the quincunx so as to be alined in two directions 60 with other piles. In Fig. 5 the shorter piles 1" are driven between longer piles 1 after the longer piles have been driven. The purpose of this is to form a firmer and more solid and substantial bottom upon which the 65 concrete foundation 2 may be laid. This is done by crowding said shorter piles into the ocean floor between the previously driven long piles.

After the soft bottom has been removed 70 and the upper ends of the piles cut off to a somewhat common level, the great mass 2 of concrete is poured upon said piles and the solid and moist ocean bed and becomes integral with same. 75

Any sand which may have been loosened at the surface, especially around the piles by operations or other causes will be compressed and held fast as it is enveloped by the great body of concrete which is established upon it. 80

I claim.

1. A pier wall having an outer face provided with a bead, said face sloping from its base upward and inward toward the bead and from the ridge of the bead downward to 85 said upwardly and inwardly sloping face, the upper face of the bead sloping upwardly and inwardly and a guard extending outwardly to intercept the splash and slosh.

2. A pier wall having an outer face provided with a bead, said face sloping from its base upward and inward toward the bead and from the ridge of the bead downward to 95 said upwardly and inwardly sloping face, the upper face of the bead sloping upwardly and inwardly and a guard extending upward to intercept the splash and slosh, the face of the guard overhanging outwardly. 90

3. A pier wall having an outer face provided with a plurality of beads the outer surfaces of which extend upwardly in an inwardly and outwardly direction, one of said beads acting as a wave deflecting bead, and another of said beads acting as a guard to intercept the splash and sloppings from said 105 wave deflecting bead.

4. A pier wall having an outer face provided with a plurality of beads, and an ogee surface below said beads.

In testimony whereof, I have hereunto set 110 my hand at Los Angeles, California, this 20th day of January, 1920.

ALLAN CYRUS RUSH.

Witness:

JAMES R. TOWNSEND.
